US0D1108148S

(12) **United States Design Patent** (10) **Patent No.:** **US D1,108,148 S**
(45) **Date of Patent:** **** Jan. 6, 2026**

(54) **CONTAINER**

(71) Applicant: **YETI Coolers, LLC**, Austin, TX (US)

(72) Inventors: **Dustin Bullock**, Austin, TX (US);
Walter T. Blanchard, Manor, TX (US);
Nicholas James Lombardi, Austin, TX (US); **Michael Christopher Cieszko**, Austin, TX (US); **Derek G. Sullivan**, Austin, TX (US)

(73) Assignee: **YETI Coolers, LLC**, Austin, TX (US)

(**) Term: **15 Years**

(21) Appl. No.: **29/889,420**

(22) Filed: **Apr. 12, 2023**

Related U.S. Application Data

(63) Continuation of application No. 29/762,442, filed on Dec. 16, 2020, now Pat. No. Des. 985,937.
